UNITED STATES PATENT OFFICE

2,554,657

LOAD SUPPORTING RACK

George M. Betterton, Piedmont, and
Andrew J. Mello, Berkeley, Calif.

Application December 16, 1946, Serial No. 716,654

3 Claims. (Cl. 105—375)

1

This invention relates to load supporting racks for railway cars and the like and more particularly to resilient racks for use in railway refrigerator cars.

One of the objects of the invention is to provide a load supporting rack in which the rack is supported by resiliently deformable blocks which are separately and serially compressed during vertical movement of the load. Preferably the racks are supported by vertically aligned blocks of rubber which are separated and connected by strips of metal or like rigid material.

Another object is to provide a load supporting rack which includes a plurality of spaced resilient supporting units positively held against movement longitudinally of the supporting strips or beams without interfering with resilient vertical movements.

The above and other objects and advantages of the invention will be more readily apparent from the following description when read in connection with the accompanying drawing, in which—

Figure 1 is a partial plan view of a supporting rack embodying the invention;

Figure 2 is a partial longitudinal transverse section on the line 2—2 of Figure 1; and

Figure 3 is a partial transverse section on the line 3—3 of Figure 1.

The rack as shown is of the general type normally used in refrigerator and like railway cars to support the lading in the car. As shown, the rack is formed by a plurality of longitudinally extending beams 10 which rest on the floor of the car and extend longitudinally thereof. It will be understood that the racks may be made in a plurality of sections in which case the beams 10 for each section extend only throughout the length of the section.

A supporting strip 11 is supported on each of the beams 10, and each supporting strip as shown is formed by an inverted sheetmetal channel co-extensive with the beam and of such a size that its side flanges will fit slidably over the beam. The channels and beams may be connected by rivets or bolts 12 extending through the beam and slidably in elongated slots 13 in the side flanges of the channels. The supporting strips 11 carry a conventional rack floor illustrated as formed of spaced transverse slats 14 which are secured to the supporting strips and which extend transversely across the rack sections.

The supporting strip on each of the beams is resiliently urged upward of the beam to provide a resilient support for the rack floor so that ver-

2

tical shocks will be absorbed and the lading will be carried without damage. As shown, a plurality of resilient units indicated generally at 15 are provided on each of the beams spaced longitudinally thereof and connecting the beam to its supporting strip. As best seen in Figures 2 and 3, each of the resilient units comprises a pair of blocks 16 of resiliently deformable material such as rubber, synthetic rubber, or the like. The blocks 16 are preferably in the form of relatively thin elongated strips of a width slightly less than the width of the channels 11 and which are stacked in vertical alignment within the side flanges of the channels. The blocks are separated by a strip 17 of relatively rigid material such as sheetmetal which may be bonded or cemented to the adjacent surfaces of the blocks. As shown, each of the blocks is preferably formed with a series of recesses or openings 18 to permit deformation thereof.

With this construction the blocks are separated so that they will separately compress under a load applied to the rack. This construction limits lateral bulging of the blocks under compression so that blocks of maximum size can be used without binding on the channels. The separate and serial operation of the blocks will also produce a relatively low springing rate with high damping to minimize development of harmonic vibrations and to support the maximum load with the maximum cushioning effect.

In order to maintain the separate resilient units properly spaced, stop members 19 are provided to hold them against longitudinal movement. As shown, the stop members comprise angle brackets carried by the beams 10 and adapted to engage the opposite ends of the dividing strip 17 to limit longitudinal movement thereof. It will be noted that this construction positively prevents longitudinal movement of the supporting units without in any way interfering with free vertical compression thereof.

While one embodiment of the invention has been shown and described in detail herein, it will be understood that this is illustrative only and is not to be taken as a definition of the scope of the invention, reference being had for this purpose to the appended claims.

What is claimed is:

1. In a load supporting rack for railway cars and the like, an elongated supporting strip adapted to be mounted in a car above the floor thereof, the strip being in the form of an inverted channel, and resilient supporting means for the strip including a pair of relatively thin vertically

aligned blocks of resilient deformable material mounted between the side flanges of the strip and a relatively thin strip of substantially rigid material lying between and connecting the blocks, and lying wholly within the channel and a beam fitting slidably in the channel on which the resilient means rests.

2. In a load supporting rack for railway cars and the like, an elongated beam to be supported on the floor of the car, an elongated supporting strip of inverted channel section fitting over the beam for vertical sliding thereon, and a resilient supporting unit between the beam and the strip including a pair of vertically aligned blocks of resilient deformable material one of which is supported on the beam and the other of which engages and supports the strip, and a thin strip of substantially rigid material lying between and connecting the blocks.

3. In a load supporting rack for railway cars and the like, an elongated beam to be supported on the floor of the car, an elongated supporting strip of inverted channel section fitting over the beam for vertical sliding thereon, and a plurality of spaced supporting units between the beam and

the strip, each including a pair of relatively thin vertically aligned blocks of resilient deformable material, a thin strip of substantially rigid material lying between and connecting the blocks, and stops engaging the ends of the last-named strip to limit movement of the unit longitudinally of the beam and supporting strip.
